UNITED STATES PATENT OFFICE

2,127,158

SLIDABLE DRAWER

Harold W. Clark, Alliance, Ohio, assignor to the
McCaskey Register Company, Alliance, Ohio,
a corporation of Ohio

Original application March 2, 1936, Serial No.
66,620. Divided and this application August
24, 1936, Serial No. 97,581

4 Claims. (Cl. 45—94)

The present invention is a division of my co-pending application Serial No. 66,620 for Cash registers, filed March 2, 1936, and refers more particularly to the slidably mounted cash or credit file drawers mounted therein, and has for its object the provision of means for slidably supporting the drawers and for opening them when desired.

The above, together with other objects which will be apparent from the drawings and following description, or which may be later pointed out, may be attained by constructing the improved slidable drawers in the manner illustrated in the accompanying drawings, in which

15 Figure 1 is a side elevation partly in section showing the lower portion of a register provided with a cash drawer and a credit file drawer embodying the invention taken as on the line 1—1, Fig. 2;

20 Fig. 2, a rear elevation, with parts broken away, of the lower portion of the register, showing the two drawers as illustrated in Fig. 1 taken as on the line 2—2, Fig. 1.

Fig. 3, an enlarged, fragmentary detail sectional view taken as on the line 3—3, Fig. 1; and

25 Fig. 4, an enlarged, detail sectional view, taken as on the line 4—4, Fig. 1.

And Fig. 5, a plan sectional view taken as on the line 5—5, Fig. 2.

30 Fig. 6, a perspective view of one drawer, telescopic plate and latching means; and

Fig. 7, a detail sectional view taken as on the line 7—7, Fig. 1.

Similar numerals refer to similar parts throughout the drawings.

The invention is illustrated as applied to a combined cash and credit register, but since the present invention is directed to the drawers per se, the register is not illustrated in detail, but 40 only a fragmentary portion thereof is shown and described.

As is usual practice, in registers of the general type indicated, each bank of keys has associated therewith a link connected to a bell crank lever 45 through which the type bars are operated, this link being allowed to move forward by the depression of any key in the corresponding bank.

These links are indicated at 60, and the lower arms of the bell crank levers are shown at 61, 50 fulcrumed upon the frame at 62 and pivotally connected, as at 63, to the corresponding links.

A rack bar 52, operated by the register in the manner disclosed in my copending application above referred to, may mesh with a pinion 73, 55 fixed upon the sleeve 74 which is slidably keyed

upon the vertical shaft 75, journaled through the rear portion of the frame of the machine.

The sleeve 74 may be keyed upon the shaft 75 as by the longitudinal slot 76 in the sleeve engaging the stud 77 in the shaft. The shaft 75 is 5 mounted for vertical sliding movement, as well as for rotation, in its journals.

The lifting lever 85 is provided at its rear end with the angular flange 86 located beneath the collar 87 upon the shaft 75 and adapted to be 10 normally located beneath a cut-out portion of said collar (not shown), whereby raising of the lever 85 will permit the angular end 86 thereof to pass upward through said cut-out portion of the collar without moving the shaft 75. 15

The apparatus illustrated is shown provided with a cash drawer 89 located beneath the adding and listing mechanism and a credit drawer 90 located beneath the cash drawer. These drawers are slidably mounted within chassis indicated generally at 91 and 92 respectively and enclosed by housings 93 and 94 respectively. A pull spring 95 is provided for normally urging the cash drawer to open position and a pull spring 96 is similarly provided for normally urging the 25 credit drawer to open position.

For the purpose of normally holding the cash drawer in closed position, a latch bolt 97 is vertically slidably mounted within a bracket 98 and normally urged downward as by the spring 101, 30 into the recess 99, formed in a plate 100 extending across the rear upper portion of the cash drawer.

In the same manner, the credit drawer is normally held in closed position by the latch bolt 102 vertically slidably mounted in the bracket 103 and normally urged downward into engagement with the recess 104 in the plate 105, by means of the spring 106.

A lifting bar 107 is pivoted upon some stationary portion of the machine and located through a notch 109 in the rear side of the latch bolt 97. It will be seen that by raising the free end of the lifting bar 107, the latch bolt 97 may be raised out of engagement with the recess 99 45 in the plate 100 of the cash drawer 89, permitting the spring 95 to open said drawer.

A similar lifting bar 110 is pivoted upon some stationary portion of the machine and located through a notch 112 in the latch bolt 102, so that 50 by raising the free end of the lifting bar 110, the latch bolt 102 may be raised out of engagement with the recess 104 in the plate 105 of the credit drawer, permitting the spring 96 to open said drawer. 55

Collars or washers 113 and 114 are fixed upon the sleeve 74 above and below the pinion 73 to form a guide for the same upon the rack bar 52. Just above the upper collar 113 a collar 115 is fixed upon the shaft 75 as by the set screw 116 and provided with a lift finger 117 adapted to be moved to position beneath the free end of the lifting bar 107.

A similar collar 118 is fixed upon the lower portion of the shaft 75 as by the set screw 119 and provided with a similar lift finger adapted to be moved into position beneath the free end of the lifting bar 110.

The drawers may be slidably mounted within the chassis frames in any suitable manner, the preferred construction being illustrated, in which the credit drawer 90 is mounted for horizontal sliding movement within the inverted U-shaped chassis frame members 92, by means of a series 20 of channel members and rollers.

For this purpose a channel member 121 is fixed to the inner sides of the U-shaped chassis frames 92 at each side of the drawer 90. An oppositely disposed channel member 122 is telescoped over each channel member 121 and carries a roller 123 which rolls within the channel 121. This channel 122 is connected to the downturned ends 105a of the plate 105 and to the forwardly disposed angular ends 124 of the bar 125 as by the bolt 126 upon which the roller 123 is journaled, and rides upon the roller 123' mounted on the chassis frame.

Rollers 127 are carried upon the outer sides of the channel 122 and received in a channel 128 fixed to each side of the drawer 90, thus slidably supporting the drawer upon said rollers. For the purpose of taking up any lost motion, the bar 125 has springs 129 fixed upon its rear side for engagement with the back wall of the housing 40 when the drawer is in closed position.

The spring 96 may be connected at its forward end to a stud 130 depending from the bar 131 spaced above the bottom wall of the housing as by the studs 132. The rear end of the spring 96 may be connected to the credit drawer catapult 133 which is slidably mounted upon the bar 131 and provided with the upturned angular flange 134 at its rear end for contacting with the rear end of the credit drawer.

50 Stop members in the form of plates 135 may be spot welded or otherwise fixed to the rear end of the drawer 90 and depend below the bottom thereof for engagement with the frame portion 136 at the front of the credit drawer housing to prevent the drawer from being accidentally withdrawn entirely from the housing. A bumper 137 is fixed upon the bar 131 to limit the forward movement of the credit drawer catapult 133.

A cam bar 138 is fixed to each side of the chassis frame 92 and provided with the tapered forward and rear ends 139 and 140 respectively. A latch lever 141 is pivoted as at 142 upon the side of the drawer and provided at its free end with a reduced extension 143 to which is connected one end of a pull spring 144, the other end thereof being connected to any suitable stationary point upon the drawer, being shown as connected to the rear end of the channel 128. A pin 145 is carried by the lever 141 near the free end thereof for contact with the inclined ends and lower edge of the cam bar 138.

A locking finger 146 depends from each side of the plate 105 and is adapted to engage the free end of the latch lever 141 as shown in Fig. 2, the lower end of said finger being inclined for-

wardly and upwardly as at 147 for a purpose to be later described.

A stop block 148 may be fixed upon each side of the credit drawer 90 just beyond the rear end of the channel 128 for engagement with the rear-most roller 127 as the drawer is opened. One or more stop pins 149 may be carried upon leaf springs 150 fixed at their rear ends to the underside of the plate 105, said stop pins being adapted for engagement with the front frame portion 151 10 of the credit drawer housing.

For the purpose of slidably mounting the cash drawer within its housing, a channel 152 may be fixed to each side of the cash drawer 89 as well as to the depending flanges 100a of the plate 100, said channel being arranged to roll upon rollers 153 carried by the chassis members 91. Rollers 154 are carried by the drawer 89 and adapted to roll in the channel members 155 fixed to the chassis members 91.

20 A cash drawer catapult 156 is slidably mounted upon the bar 157 spaced above the bottom wall of the cash drawer housing as by the studs 158, said catapult being provided with a bumper 159 for engagement with the rear end of the cash drawer. The spring 95 is connected at its forward end to a pin 160 depending from the bar 157 and at its rear end to the catapult 156. A stop block 161 is fixed upon the bar 157 to limit the forward movement of the catapult 156. Depending stop fingers 162 are provided at the rear end of the cash drawer 89 for engagement with the front portion 163 of the cash drawer housing to prevent accidental displacement of the cash drawer from the housing.

35 Assuming that a cash transaction is to be made, when the amount is set up and the proper keys have been depressed, the corresponding link 60 will be allowed to move forward, as in usual practice, by the operation of the machine, and the 40 rack bar 52 will be operated in the manner disclosed in my copending application above referred to.

During this operation of the rack bar the pinion 73 will be rotated, and in turn will rotate the shaft 45 75 to a position bringing the lift finger 117 beneath the free end of the lifting bar 107, and rotating the collar 87 upon said shaft to such position that the cut-out portion of said collar is not located above the angular end 86 of the lifting lever 85. As the operation of the machine progresses the lever 85 will be lifted, the angular end 86 thereof engaging the collar 87 and slidably moving the shaft 75 upward.

The lift finger 117 having been positioned beneath the free end of the lifting bar 107, this upward movement of the shaft 75 will raise the lifting bar 107 and through the same will raise the latch bolt 97, against the pressure of the spring 101, out of engagement with the recess 99 60 in the plate 100, releasing the cash drawer and permitting the spring 95, acting through the cash drawer catapult 156, to quickly slide the cash drawer into open position.

As the lifting bar 107 is raised to withdraw the 65 latch bolt 97 and release the cash drawer, the pin 168 carried by said lifting bar will be raised out of engagement with the end of the taper 165, permitting the spring 167 to cause the taper to strike the gong 164 a sharp blow, giving an audible signal that the cash drawer is being opened.

If a charge transaction is made, the amount may be set up in the machine, and the proper keys are depressed in order that the credit drawer will be opened when the machine is operated. As 75

disclosed in my copending application above referred to, the rack bar 52 will be operated sufficiently to rotate the shaft 75 so as to bring the lift finger of the collar 118 beneath the free end 5 of the lifting bar 110.

Thus, when the shaft 75 is raised by means of the lifting lever 85, the lift finger will raise the lifting bar 110, pulling the latch bolt 102 out of the recess 104 of the plate 105, releasing the 10 credit drawer and permitting the spring operated catapult 133 to push the credit drawer open.

As the drawer moves toward open position, the pin 145 on the lever 141 will ride down the inclined end 140 of the cam bar 138 and onto the 15 lower edge of said cam bar, releasing the lever 141 from engagement with the finger 146, thus disconnecting the plate 105 from the credit drawer so that as said drawer is pulled out to the 20 fully opened position, the accounts at the rear-most end of the drawer will be accessible.

I claim:

1. Apparatus including a chassis frame, a drawer slidably mounted within said frame, a telescoping plate detachably connected to said drawer, a latch bolt cooperating with said telescoping plate for normally retaining the drawer in closed position, spring means for normally urging the drawer to open position, means for releasing the latch bolt, and means for disengaging the telescoping plate from the drawer after the latch bolt has been released.

2. Apparatus including a chassis frame, a drawer slidably mounted within said frame, a telescoping plate detachably connected to said drawer, a latch bolt cooperating with said telescoping plate for normally retaining the drawer 30

in closed position, spring means for normally urging the drawer to open position, means for releasing the latch bolt, means for disengaging the telescoping plate from the drawer after the latch bolt has been released, and means for preventing re-engagement of the telescoping plate with the drawer until the drawer is returned to closed position. 5

3. Apparatus including a chassis frame, a drawer slidably mounted within said frame, a telescoping plate detachably connected to said drawer, a latch bolt cooperating with said telescoping plate for normally retaining the drawer in closed position, spring means for normally urging the drawer to open position, means for 10 releasing the latch bolt, means for disengaging the telescoping plate from the drawer after the latch bolt has been released, and means for preventing re-engagement of the telescoping plate with the drawer until the drawer is moved to a 15 predetermined position.

4. Apparatus including a chassis frame, a drawer slidably mounted in said chassis frame, a telescoping plate, a locking finger carried by said telescoping plate, a latch lever mounted upon 25 said drawer and engaging said locking finger for normally connecting the telescoping plate to the drawer, a latch bolt for engagement with the telescoping plate for normally holding the drawer in closed position, spring means normally urging 30 the drawer toward open position, means for releasing the latch bolt, and a cam bar upon the chassis frame cooperating with the latch lever for disengaging the telescoping plate from the drawer after the latch bolt has been released. 35

HAROLD W. CLARK.
